STUBBLE DESTROYERS

Franz B. Larson, Memphis, Tenn.

Application September 24, 1953, Serial No. 382,074

5 Claims. (Cl. 126—271.2)

This invention relates to a new and useful device primarily adapted for destroying the stubble such as that left surrounding lawns and other grass plots while minimizing the labor and effort necessary to effectuate the removal and destruction of such stubble.

As is well known, one of the primary problems of the home owner is in connection with the cutting of the grass areas adjacent and contiguous to his home, and more particularly the problem is accentuated in connection with the areas immediately adjacent surfaces such as sidewalks and the like in which mowing of the grass of the lawn is rendered difficult in virtue of the variations in surfaces, frequently leaving an undesirable fringe or stubble adjacent such areas.

It also is well known that similarly adjacent areas such as flower beds, with which many lawn areas are decorated, it is extremely difficult to remove grass and weeds by cutting immediately adjacent such areas because of the danger of damage to the flowers contained in such beds.

The present invention particularly relates to a device for removing undesired stubble from the areas just mentioned and specifically contemplates the employment of a conventional burner device, such as a blow torch, for accomplishing this purpose. The prior art has heretofore disclosed the employment of flame devices and burners for use upon and in connection with the removal of undesired residue, such as weeds and the like, from cultivated fields. Such devices, however, are not satisfactory for the purpose for which the present invention is designed, and lack the mobility and accuracy necessary for satisfactorily accomplishing the purposes of the present invention, all of which obstacles and short-comings are overcome in the present device.

The principal object of the present invention is to provide a stubble destroying device comprising a burner and a portable frame adjustably and shiftably supporting the burner for employment in connection with various areas desiring treatment.

A further object of the present invention is to provide a supporting frame-carrying guard members and flame directional tubes adjacent and associated with such guard members, together with a shiftable and adjustable cradle for supporting a burner device for positioning selectively in flame communication with the respective tubes and guard members.

A further object of the invention is to provide a portable frame adapted for supporting a blow torch in adjustable positions of flame discharge to provide for selective stubble removing by burning along areas of choice.

A further object of the invention is to provide in such a device an external outrigger baffle to provide an external guard limiting the extent of the area to be burningly treated by the flame discharge from such a burner; and

A further object of the invention is to generally improve the design, construction and efficiency of devices for destroying undesired stubble in grass areas.

The means by which the foregoing and other objects of the invention are accomplished and the manner of their accomplishment will readily be understood from the following specification upon reference to the accompanying drawings, in which:

Fig. 1 is a side elevational view of the preferred embodiment of the present invention illustrating the supported burner in one position of shift.

Fig. 2 is a front elevational view of the device of Fig. 1 with the burner device shifted to an opposite position of angularity.

2

Fig. 3 is a top plan view of the supporting frame work and carriage of the present invention with the burner device shown in phantom and with the burner engaging means being shown shifted to a further position of shift.

Fig. 4 is a front elevational view of the device of the present invention with the burner in the position of Fig. 1 and illustrating a further modification and adaption of the device; and

Fig. 5 is a top plan view of the supporting frame and carriage of the present invention with the burner device removed and including the additional modification of Fig. 4.

Referring now to the drawings in which the various parts are indicated by numerals, it will be seen from the drawings that the present invention primarily consists of a burner device 11, consisting in the preferred embodiment of a substantially conventional blow torch which is shiftably and adjustably mounted upon a suitable wheeled carriage frame and burner engaging means. As is conventional the blow torch 11 includes a directional jet 13 for the purpose of directing the combustible mixtures delivered from the blow torch under pressure, which when ignited will produce an extremely hot flame which is jetted in accordance with the direction of the jet 13.

The supporting carriage of the present invention comprises a substantially rectangular frame work 15, to the rear of which frame work is fixed an upwardly and angularly extending handle 17. Adjacent the rear of the frame work 15 the frame work is suitably supported as by wheels 19 carried in brackets 21 which are fixed to the sides of the frame work. Brackets 21 support the wheels 19 for rotational engagement as with the surface of the ground 23 and support the frame work 15 for movement over the ground.

Means for engaging and holding the blow torch 11 are provided in a cradle 25, preferably consisting of a girth strap 27 and a saddle strap 29. The cradle 25 is rockably and shiftably connected to frame work 15 in the manner hereinafter described, and is adapted to surround and clampingly engage the body of blow torch 11 so as to retain same in desired position supported upon the wheeled frame work 15. Preferably girth strap 27 of cradle 25 consists of an elongated strap provided with a substantially arcuate central portion and radially projecting side portions 30, the side portions terminating in angularly bent end portions 31. It will be observed that the radially extending portions 30 are arranged in substantial alinement and that the end portions 31 are bent substantially perpendicularly to the radially extending portions 30 and are turnably engaged against the inner surfaces of the side members of frame work 15. Preferably the girth strap 27 is turnably and rockably connected to the frame work 15 by bolts 32 which extend through the angularly bent end portions 31 and through suitable apertures 35 formed in each of the side members of frame work 15 and are provided with suitable wing nuts 33 for ready tightening or loosening of the attachment as desired.

It is preferred that the side members of frame work 15 each be provided with a plurality of longitudinally spaced apertures 35 to provide for longitudinal adjustment of position of cradle 25 relative to the frame work. As will be seen the bolts 32 may be extended through a selected set of apertures 35 to establish the desired position for the attachment of the girth strap 27 to the frame work 15, and consequently thereby to establish the longitudinal position of cradle 25 relative to the frame work.

Saddle strap 29 is detachably and adjustably connected to the girth strap 27, the saddle strap 29 being provided with end portions 37 which are disposed substantially parallel to the radially extending portions 30 of the girth strap 27 and are detachably connected thereto, as by bolts and wing nuts 39.

As can be seen from the drawings the girth strap 27 and saddle strap 29 when connected together are adapted to form a substantially circular cradle which is particularly adapted to embrace the body of a burner, such as the blow torch 11, and upon tightening of the bolts and nuts 39 to clampingly engage the body of such a blow torch so as to attach same firmly to the cradle 25. As is apparent the longitudinal position of the cradle 25, and,

when engaged by the cradle, of blow torch 11, may be established through a selection of desired apertures 35 of the frame work and the engagement therethrough of bolts 32 engaging the end portions 31 of the girth strap.

Rigidly secured to the frame work 15 and depending therefrom are a pair of flame directional tubes 41 which are preferably provided with suitable perforations so as to provide oxygen for combustion to the flame to prevent snuffing thereof. The tubes 41 are positioned so as to laterally flare outwardly from the sides of frame work 15 as clearly shown in the drawings and in addition are positioned so as to extend downwardly and forwardly as well as outwardly from their upper ends. The tubes 41 are illustrated as rigidly connected to the frame work by suitable bracket means 43, but it will be understood that other means of rigidly connecting the tubes 41 in the desired positions of angularity relative to the frame work may be employed if desired.

It will be observed that the upper ends of the tubes 41 are preferably spaced slightly below the lower edge of the frame work 15 and that the lower ends of the tubes 41 are spaced above the ground level contacted by the ground wheels 19. Rigidly fixed to the tubes 41 adjacent the lower ends of the inner surfaces of the tubes are flame shielding guard plates 45, the lower edges of guard plates 45 being adapted to serve as supports and slides for the forward end of frame work 15, maintaining same in desired substantially horizontal position, contacting the ground 23 for such purpose. The guard plates 45 flare outwardly from the frame work and are disposed at an angle to the vertical substantially equal to the outward flaring angularity of the tubes 41. However, it will be observed that the guard plates 45 do not project angularly forwardly in the same manner as to the tubes 41.

It will be seen that the guard plates 45 are connected to the exterior of tubes 41 above the lower ejection end of the tubes and accordingly serve to guard against any burning by the flames ejected through the tubes 41 inwardly of the guard plates, insuring that all such burning will take place outwardly therebeyond.

In the embodiment of the invention as shown in Figs. 4 and 5, the supporting frame work, heretofore described, is provided with an additional outrigger baffle for providing an outer protection against the spread of flames ejected from a selected tube 41. In this embodiment the frame work 15 is provided with a plurality of tube-like sockets 47 adapted to removably receive rod-like brackets 49, the brackets 49 preferably each comprising an inverted, substantially J-shaped member in which the short leg of the J is adapted to be removably inserted in the leg of the brackets 47 and the longer leg of the J extends downwardly below the level of the frame work 15, with the web of the J-brackets 49 extending substantially horizontally laterally outwardly from the frame work 15.

Removably secured to the downwardly extending outer legs of the brackets 49 is an outrigger baffle 51 which is preferably provided with the tube-like attachment members 53, preferably provided with clamp screws 55, the attachment members 53 being adapted to slidably embrace legs of brackets 49, and when so positioned to be fixed in desired position by the setting of clamp screws 55.

In the use of the device blow torch 11 is mounted in cradle 25. In order to properly position the blow torch it is desired that the longitudinal positioning thereof be adjusted until the directional jet 13 is in substantially the same plane to permit registry with a selected directional tube 41, as shown in Fig. 1 for example. Such longitudinal adjustment is accomplished by selecting a desired pair of opposite apertures 35 in the frame work 15 and extending the cradle bolts 32 therethrough, fixing wing nuts 33 to the bolts and thus attaching the cradle to the frame work in desired longitudinal position.

If it is necessary after the blow torch has been mounted in the cradle and it is not desired to remove the blow torch therefrom, the cradle 25 may be shifted to the position, such as shown in Fig. 3, in which the blow torch 11 will be supported in substantially vertical position, in which position it is most convenient to recharge the blow torch with its necessary combustion elements and in which position it is further more simple to ignite the combustion materials for flame ejection from the directional jet 13. In such position the blow torch is firmly clamped in the cradle 25 by the tightening of the saddle strap 29 through tightening of the bolts and nuts 39, thus effecting

clamping of the blow torch body between the saddle strap 29 and the girth strap 27.

With the blow torch ignited and ready for operation the cradle may be rocked about its pivotal connections to the frame work through the bolts 32 to a desired position of angularity relative to one of the directional tubes 41. Preferably the saddle strap 29 is slightly loosened to permit a rotation of the blow torch relative to the cradle 25 so as to move the end of directional jet 13 into alignment with a selected directional tube 41. It will be observed that by virtue of the positioning of the tubes 41 just below the lower level of the frame work 15 an air space, desirable for proper combustion, is maintained between the end of jet 13 and the upper end of the tube 41 selected. When the positioning of the blow torch as desired has been accomplished, the bolts and nuts 39 may be again tightened to clamp the blow torch body in the cradle and with the bolts and nuts 32, 33 completely tightened to maintain the cradle in rocked position relative to the frame work 15, the device is ready for operation.

With the blow torch ignited flame is ejected from the jet 13 through a selected tube 41 and is directed thereby downwardly against the outer surface of the guard plate 45 connected to the selected tube 41. The guard plate 45 is effective to prevent any burning of grass or other materials inwardly of the guard plate and serves to partially deflect the flame discharged through the selected tube 41 in the desired direction.

As illustrated in Fig. 2 of the drawings, the device may be then alined alongside a surface, such as the sidewalk 57 with a guard plate 45 resting on ground 23 in desired adjacency to the edge of sidewalk 57. The flame emitted from the selected tube 41 is directed toward any foliage or other substance above the level of the ground and between the guard plate 45 and the edge of the sidewalk 57. The device may then be moved along a path parallel to the edge of sidewalk 57 and effective burning of the undesired stubble adjacent such sidewalk satisfactorily accomplished.

As is apparent it is sometimes desirable where the sidewalk 57 is disposed in an area which is inaccessible to burning from one or the other side of the device, as for example when in conjunction with a terrace, the blow torch 11 may be rotationally shifted by loosening the saddle strap 29 and rotating the blow torch relative to cradle 25, shifting the burner to an opposite position of angularity in alinement with the other of the tubes 41.

It is also desirable in areas, such as for example adjacent flower beds, to provide for a positive outer baffling against the outward extent of the flames directed through a selected tube 41. For the purpose the outrigger baffle 51 may be mounted in the sockets 47, positioned outwardly of the selected tube 41 and spaced from the related guard plate 45, as best shown in Fig. 4. The device may then be positioned with the outrigger baffle 51 riding inwardly of a flower bed, such as one containing flowers 59, and the flames directed through the selected tube 41 will effectively burn off the undesired grass and other stubble between the guard plate 45 and outrigger baffle 51.

It will be understood that while the foregoing description has described and shown the burner as a blow torch 11, that other types of burning devices may be mounted in the present frame work for the purposes described without departing from the present invention.

I claim:

1. In a device for destroying undesired stubble by burning, which includes burner means, a frame, a pair of flame directional tubes rigidly connected to said frame adjacent its front end, said tubes depending from said frame and flaring forwardly and oppositely outwardly therefrom with the upper ends of said tubes spaced below the level of the frame and the lower ends of the tubes spaced above ground level, each said tube having a ground-contacting guard plate rigidly fixed adjacent and inwardly of the lower end of the tube, a cradle for supporting said burner means, said cradle being rockably and longitudinally adjustable relative to said frame to establish burner position relative to said tubes, said cradle including a releasably connected saddle strap for clampingly engaging said burner means when mounted in said cradle and being releasable for flame alinement of said burner means with one of said

tubes, said guard plates being positioned to shield the area adjacent and inward of the lower ends of said tube from flames when delivered through said one tube, and a baffle removably connected to said frame and supported spaced outwardly from said one tube to limit the area affected by flame delivered through said one tube.

2. In a device for destroying undesired stubble by burning, which includes burner means, a frame, a pair of flame directional tubes rigidly connected to said frame adjacent its front end, said tubes depending from said frame and flaring forwardly and oppositely outwardly therefrom with the upper ends of said tubes spaced below the level of the frame and the lower ends of the tubes spaced above ground level, each said tube 15 having a ground-contacting guard plate rigidly fixed adjacent and inwardly of the lower end of the tube, a cradle for supporting said burner means, said cradle being rockably and longitudinally adjustable relative to said frame to establish burner position relative to said tubes, said cradle including a releasably connected saddle strap clampingly engaging said burner means when mounted in said cradle and being releasable for flame alinement of said burner means with one of said tubes, said guard plates being positioned to shield the area adjacent and inward of the lower ends of said tubes from flames when delivered through said one tube.

3. In a device for destroying undesired stubble by burning, which includes burner means, a frame, a pair 30 of flame directional tubes rigidly connected to said frame adjacent its front end, said tubes depending from said frame and flaring oppositely outwardly therefrom with the lower ends of the tubes spaced above ground level, each said tube having a ground-contacting guard plate 35 rigidly fixed adjacent and inwardly of the lower end of the tube, a cradle for adjustably supporting said burner means, said cradle being rockably adjustable relative to said frame to establish burner position relative to said tubes, said guard plates being positioned 40 to shield the area adjacent and inward of the lower ends of said tubes from flames when delivered through said one tube.

4. In a device for destroying undesired stubble by burning, which includes burner means, a frame, flame directional tube means rigidly connected to said frame, said tube means depending from said frame into adjacency with ground level, ground-contacting guard plate means rigidly fixed to said tube means, a cradle for supporting said burner means, said cradle being rockably adjustable relative to said frame to establish burner position relative to said tube means, said guard plate means being positioned to shield the area adjacent and inward of the bottom of said tube means from flame when delivered through said tube means.

5. Means for supporting and transporting a burner for use in destroying undesired stubble by burning, which comprises a frame, a pair of flame directional tubes rigidly connected to said frame adjacent its front end, said tubes depending from said frame and flaring forwardly and oppositely outwardly therefrom with the upper ends of said tubes spaced below the level 20 of the frame and the lower ends of the tubes spaced above ground level, each said tube having a ground-contacting guard plate rigidly fixed adjacent and inwardly of the lower end of the tube, a cradle for supporting said burner means, said cradle being rockably and longitudinally adjustable relative to said frame, said cradle including a releasably connected saddle strap for clampingly engaging said burner means when mounted in said cradle and being releasable for flame alinement of said burner means with one of said tubes, said guard plates being positioned to shield the area adjacent and inward of the lower ends of said tubes.
